(57) **CLAIM**

The ornamental design for probe unit for a medical scanning device, as shown and described.

DESCRIPTION

FIG. 1 is a top perspective view of a probe unit showing my design;

FIG. 2 is a top plan view thereof;

FIG. 3 is a right side elevational view thereof, the left side elevational view being a mirror image thereof;

FIG. 4 is a bottom plan view thereof; and,

FIG. 5 is a bottom perspective view thereof.
